UNITED STATES PATENT OFFICE.

WALTER M. SCHWARTZ, OF PHILADELPHIA, PENNSYLVANIA, ASSIGNOR TO THE PHILADELPHIA TEXTILE MACHINERY COMPANY, OF PHILADELPHIA, PENNSYLVANIA, A CORPORATION OF PENNSYLVANIA.

DRYING-MACHINE.

1,181,039.

Specification of Letters Patent. Patented Apr. 25, 1916.

Application filed December 4, 1914. Serial No. 875,537.

To all whom it may concern:

Be it known that I, WALTER M. SCHWARTZ, a citizen of the United States, residing in Philadelphia, Pennsylvania, have invented 5 certain Improvements in Drying-Machines, of which the following is a specification.

My invention relates to certain improvements in drying machines of the type in which an endless chain travels through a 10 drying compartment and the material to be dried is carried by the chain.

One object of the invention is to construct the conveying means so that a single chain can be employed to carry the material to be 15 dried.

A further object of the invention is to mount, at intervals on the chain, horizontal supports, or bars, for the material.

A still further object of the invention is 20 to construct the mechanism so that these supports can be mounted on each side of the chain.

In the accompanying drawings: Figure 1 is a front view of my improved machine; Fig. 2 is a sectional plan view on the line 25 $a-a$, Fig. 1; Fig. 3 is a side view; Fig. 4 is a longitudinal sectional view of a portion of the apparatus at the feed end thereof; Fig. 5 is an enlarged sectional view through the track and the conveyer, showing the 30 conveyer suspended from a rail; and Fig. 6 is a perspective view of a portion of the chain and the horizontal supports connected thereto.

Referring to the drawings, 1 is the casing 35 of the conveyer made in any suitable manner. In the present instance, it consists of a frame composed of a series of metal shapes 2 and mounted on the frame is a series of panels 3, which inclose the chamber. It will 40 be understood that the length of this casing will depend upon the material to be dried as it may be of any length desired. In the upper portion of the drying chamber is a fan 4, mounted on a suitable shaft 5, which 45 has its bearings in a frame 6 and is driven from a horizontal shaft 7 through bevel gearing. While in the drawings only one fan is shown, it will be understood that any number of fans may be used according to the length of the casing. At each side of the chamber formed by the casing are coils 50 8 of heating pipes so that, when the fan is in motion, there is a constant circulation of

air through the casing, the steam pipes heating the air to the proper temperature. 55

9 is a series of longitudinal rails, spaced a given distance apart, and located at a proper height to allow material to be suspended from the conveyer which travels on the rails. These rails are made as shown in 60 Fig. 5, and have inturned flanges 10 on which travel the wheels 11 from which is suspended the chain 12. This chain 12 is composed of a series of links 13 and the links 13^a have the brackets 14 on which the 65 axles of the wheels 11 are mounted, and also have depending portions 15. In the present instance, projecting from each side of this depending portion 15 are spindles 16 on which are mounted spools 17. These spools 70 are preferably held from turning by any suitable means, so that the material thereon will not accidentally slide from the spools. Each of the spools is preferably provided with a head so as to retain the material in 75 position but, in some instances, where the spools are of a suitable length, or the spindles are used without the spools, then the heads may be dispensed with.

It will be understood that the present machine is designed for drying comparatively narrow material, such as narrow woven fabric. The machine, however, may be designed for different widths of material without departing from the essential features of the invention. Furthermore, the spindles may be located at one side only of the chain when necessary and while I have illustrated mechanism for feeding a continuous band of fabric to the machine, single pieces of material may be mounted on the horizontal spindles, or spools, traversed through the machine without departing from the spirit of the invention. In this apparatus, a single endless conveyer chain is 90 used and it enters the casing through the opening 18, Fig. 2, and is supported by the first rail and passes around a sprocket wheel 19 at the rear end of the machine and returns and passes around a sprocket wheel 100 20. There is a series of these sprocket wheels 19 and 20, at the rear and at the front of the machine, as shown in the plan view, Fig. 2, and after the chain traverses the last rail 9 it passes out through the opening 21 and then around a sprocket wheel 105 22

and a sprocket wheel 23, where it again enters the opening 18.

A sprocket wheel 24 is arranged so as to take up any slack in the chain in order that 5 the chain will be taut throughout the entire apparatus. A rail 25 supports the chain as it travels from the sprocket wheel 22 to the sprocket wheel 24 and, as above remarked, the material may be placed on the spindles, 10 or spools, by hand and removed therefrom by hand, or it may be placed thereon by machinery and automatically removed by mechanism which I will now proceed to describe. Mounted in front of the drier is a 15 frame 26 on which are mounted the feed rolls 27, 28 and 29, which feed the fabric forward in the present instance and into the casing. The roll 29 is so located that it extends into the chamber formed by the casing 20 so that the fabric α is discharged from the inner end of the roll 29 and passes down between two spindles, as clearly shown in Fig. 4, and the mechanism for driving the 25 chain is so mounted that it will move to allow a loop of the fabric to be formed between the two spindles. In order to prevent the loop being formed from disturbing the loop previously formed, a detent in the 30 form of a pivoted arm 30 is located so as to engage the fabric on the spindle between the two loops and it will hold the fabric throughout the formation of the loop being formed. This detent is released as the chain moves forward and engages the fabric on 35 the next spindle and so on as the material is fed to the apparatus. 31 is a clutch controlled by the lever 32 for throwing the feed mechanism out of gear when it is necessary. At the discharge end of the machine is a 40 roller 33 over which the fabric passes after it has been dried and it passes between two rollers 34 and 35 and into a hopper 36 and through a discharge spout 37, which is

moved to allow the material to fall on a platform, or floor, without tangling. In 45 the present instance, there is sufficient width to the feed rolls to take two strands of material and to feed one strand to the spindles on one side of the chain and the other strand to the spindles on the opposite side. The 50 discharge rollers 33, 34 and 35 are of sufficient width to take both strands, but there are two hoppers at the discharge end and 55 two spouts. One strand is fed to one hopper and spout and the other strand is fed to the other hopper and spout and these spouts are spaced a sufficient distance apart in order that one pile of material will not become entangled with the other pile. Any suitable mechanism may be used for driving the discharge rollers and for reciprocating the 60 spouts.

I claim:

The combination of a casing; means for circulating the air in the casing; means for 65 heating the air; a series of guide rails spaced apart; a series of sprocket wheels in line with the rails and at each end of the chamber; a single chain having wheels spaced apart and arranged to travel on the rails, 70 the chain passing around the several sprocket wheels; a series of spindles arranged horizontally and carried by the chain below the rails; means for feeding material to the spindles after they have entered the chamber; and means for removing the material from the spindles before 75 they leave the chamber.

In testimony whereof, I have signed my name to this specification, in the presence of 80 two subscribing witnesses.

WALTER M. SCHWARTZ.
